UNITED STATES PATENT OFFICE.

HIRAM R. FERRIS, OF CLEVELAND, OHIO.

LIFTING-JACK.

SPECIFICATION forming part of Letters Patent No. 249,235, dated November 8, 1881.

Application filed September 27, 1881. (No model.)

To all whom it may concern:

Be it known that I, HIRAM R. FERRIS, of Cleveland, in the county of Cuyahoga and State of Ohio, have invented certain new and useful Improvements in Lifting-Jacks; and I do hereby declare the following to be a full, clear, and exact description of the invention, such as will enable others skilled in the art to which it pertains to make and use it, reference being had to the accompanying drawings, which form part of this specification.

My invention relates to lifting-jacks; and it consists in the peculiar construction of the same, as will be hereinafter fully set forth and claimed.

In the drawings, Figure 1 is a side elevation of my jack. Fig. 2 is a vertical cross-section of the head and grasping device of the same. Fig. 3 is a view of the head with part removed, 20 showing the grasping device within said head, and in a closed position. Fig. 4 is also a view of the head with part removed, showing the grasping device in an open position, and the device for locking said grasping device in said 25 open position. Figs. 5 and 6 are sectional views, showing different constructions of the jaws of the grasping device.

A is a post or standard, which is made hollow for the reception of the lifting-shaft. 30 B is a lifting-shaft, which is constructed to have a vertical movement, and is provided at its top with a suitable bearing-surface, B', and at its lower end with a hook or lug, B'', which extends out from the side of the standard, and 35 is particularly adapted to be used to raise rails and such like low weights. The lifting-shaft B has formed upon it a ratchet screw-thread, which is preferably mutilated, as shown in Fig. 1, by having two slots cut through it, said slots 40 being opposite each other, thus forming two ratchets, C C', (shown more clearly in Fig. 2,) one on each side of the shaft B.

D is a head, which surrounds the shaft B. This head D contains the grasping device for 45 raising the shaft B, said grasping device being composed of two jaws, E and E', which act as pawls and engage with the screw-thread or ratchets C C'. I preferably construct the jaws E and E' as shown in Figs. 2, 3, and 4, viz: 50 I provide the upper and lower ends of the interior of the head D with inclines a, b, c, and d,

on which rest the inclines at the upper and lower ends of the jaws E and E', and thus it will be seen that the gravity of the jaws E and E' will act to draw them toward the shaft B 55 and cause them to engage with the thread or ratchets C C', and that the more the head D is forced upward the tighter will the jaws E and E' hug the shaft B. This is also true of the construction shown in Figs. 5 and 6, which will 60 be easily understood from the said drawings without any further description.

F is a nut, which is adapted to turn on the shaft B, and is placed between the head D and standard A. The office of this nut is to hold 65 the shaft B at any desired point by bearing against the top of the standard A. To the head D are attached toggle arms or links G and G', said toggle-arms being also connected to the short arm of the lever H. The lever H 70 is pivoted at f to the standard A.

I is a locking device, which is placed between the jaws E' and E, and, being operated by the lever J, acts to lock the jaws E E' open and allow the shaft B to pass freely between them. 75 (See Fig. 4.) Fig. 3 shows the position of the locking device I when it is not desired to lock the jaws E and E' open.

The operation of my device is as follows: The shaft B is held up by means of the nut F, which 80 rests on the top of the standard A. The long arm of the lever H is lifted, which acts through the links G and G' to lower the head D. As the head D is lowering, the teeth on the jaws E and E' slide over the ratchet screw-thread C and C' 85 on the shaft B, which causes the said jaws E and E' to open, as shown in Fig. 4, and allows the head D to lower, the shaft B being held in position by means of nut F. When the head D has been lowered sufficiently the lever H is brought 90 down, which acts to force the head D up. Now, as the head D is forced upward, the jaws by their gravity close in toward the shaft B and engage with the ratchet-teeth C and C', and the shaft B is raised as far as the short arm of 95 the lever H will raise it. As the shaft B is raised it carries with it the nut F, and this nut F is now run downward until it rests on the top of the standard A, where it again acts to support the shaft B, while the head D is again 100 lowered, as above described. This operation is repeated until the weight is raised the de-

sired distance. To lower a weight the operation is reversed.

When no weight is on the jack, and it is desired to lower the shaft B, the lock I is brought 5 into service, as shown in Fig. 4, and locks the jaws open, when, the shaft B being held up by one hand, the nut F may be run up by the other, and thus the shaft B may be quickly lowered.

What I claim is—

- 10 1. In a lifting-jack, the combination, with a lifting-shaft provided with ratchet-teeth on opposite sides thereof, of grasping devices located on each side of the lifting-shaft, and adapted to automatically engage the teeth thereon, an actuating-lever, and devices connecting the lever and grasping devices, substantially as set forth.
- 15 2. In a lifting-jack, the combination of a shaft, B, having a screw-thread and a supporting-nut, F, with a head, D, said head having a grasping device adapted to engage with the

said screw-thread, and being operated by means of a lever, H, substantially as shown and described.

3. In a lifting-jack, the head D, said head 25 having the inclines a, b, c, and d, and the jaws E and E', said jaws being also provided with inclines adapted to rest on the inclines a, b, c, and d, substantially as and for the purpose shown and described.

4. In a lifting-jack, the combination, with a lifting-shaft provided with teeth on its opposite sides, of two grasping devices located on each side of the lifting-shaft, the locking device I, and lever J, substantially as set forth. 35

In testimony whereof I have signed my name to this specification in the presence of two subscribing witnesses.

HIRAM R. FERRIS.
